UNITED STATES PATENT OFFICE

2,006,694

STRAIGHT KNITTING MACHINE

Kenneth Howie and Charles C. Krieble, Norristown Pa., assignors to Wildman Mfg. Co., Norristown, Pa., a corporation of Pennsylvania

Application December 21, 1932, Serial No. 648,290
Renewed November 23, 1934

1 Claim. (Cl. 66—126)

The invention relates to improvements in straight knitting machines and concerns an endless band for traversing yarn guide means back and forth along the needle row with means for giving a reciprocating movement to said band. The invention also concerns means for controlling the length of movement of the endless flexible band for narrowing.

The invention consists in the features hereinafter described.

In the drawings:

Figure 1 is a diagrammatic plan view of the invention.

Fig. 2 is a diagrammatic sectional view of the invention.

Fig. 3 is a view of details relating to the reciprocating driver for the band.

Fig. 4 shows the yarn guide.

Fig. 5 is a detail view of the driver for the endless band.

In these drawings the straight row of needles is shown at 1a mounted in a needle bar 1 which is operated to cooperate with the sinkers and dividers as in well known practice. At 26 is shown a flexible endless band set up on edge with its front stretch adjacent and parallel with the needle row and its rear stretch substantially parallel with its front stretch, and with which a reciprocating driver connects to give the band its back and forth movement to traverse the yarn guide along the needle row, it being noted that the side face of the band is substantially parallel to the plane in which the needles lie. Specifically stated, this band causes the yarn guide to traverse the needle row by the circumstance that the yarn guide consisting of a tube t is mounted directly on the band. The yarn passes through this tube and is thus delivered to the needles.

The band is guided by rollers 21 where it turns from one stretch to the other, and these curved portions are further guided by curved blocks 28, and by guide members 29. The flexible endless band is of metal. It carries on its rear stretch a dog 34. This dog has a stud 35 projecting from its upper edge, which comes against a stop Rs to determine the right hand selvage, or against a stop Ls which determines the left hand selvage of the fabric.

The stops are mounted on the brackets or supporting blocks 36, one on each block. These blocks are adjustable automatically, as will be pointed out hereinafter, when narrowing or fashioning of the fabric is to be done.

The endless flexible band 26 is reciprocated by a driver 31 which reciprocates along guide

means 33 parallel with the rear stretch of the flexible band. This driver has a pawl 31a for engaging the dog 34 on its under side to impart back and forth movement to the endless flexible band in the direction of its length. The pawl has inclined shoulders 31b to engage either one of the inclined shoulders 34d on the dog 34 according to the direction, right or left, that the driver is moving. When the stud 35 on the dog 34 comes against the stop Rs or Ls, the endless flexible band is arrested, and thus the length of the stroke of the yarn guide is determined according to the width of fabric desired.

When the endless band is thus arrested the driver can proceed to the end of its stroke. For this purpose the pawl 31a will yield or recede downwardly because the inclined shoulders 31b and 34d will have a camming action and thus the pawl will be pushed down as the driver 31 continues its stroke. This recession downwardly of the pawl is caused by the pawl 31a passing the arrested dog 34 in contact with either one of the inclines 34c on its lower edge. The pawl has a stem which is borne upon by spring pressed detents 31c which restrains its free movement by frictional contact.

This pawl is restored to its uppermost position for picking up the dog 34, on its next stroke, by a restoring slide 31j carried by the driver block 31 and operated in the final part of the stroke of said driver in either direction by coming against a fixed stop C, there being one of these fixed stops at each end of the stroke of the driver. The controller slide 31j projects from the driver block at both the right and left sides thereof, so that on either stroke one end or the other of said controller slide will contact with one of the stops C and the slide will be arrested while the driver continues a slight additional distance in completing its stroke, and thus the lower end of the stem of the pawl which is cam shaped will ride up either one or the other of the inclined walls of the V shaped notch 31h, thus restoring the pawl to its upper operative position for again engaging the dog 34.

The pawl restoring slide is under frictional restraint of suitable springs located for instance at 31k.

The driver block 31 is operated back and forth along the guide rails 33 by an endless band 30, passing around guide wheels such as at 30a arranged at opposite sides of the machine. The driver block 31 is clamped to this band by screws 32. The endless drive band 30 is clamped to an arm of slur cock carrier 37, guided on the fixed

5 rail 37a forming a part of the frame. The slur cock is reciprocated along rail 37a by a rotary reciprocating member 38 having a spiral rib 38a thereon engaged by rollers, shown at 37c, mounted on a post or posts 37b, which projects up from the slur cock carrier 37. This rotary screw threaded member 38 is given rotary reciprocating movement in any suitable manner, as for instance, by an oscillating toothed segment which drives gearing connected to the said spiral or screw member. This oscillating rack or segment is indicated generally at 38c and the gearing at 38b, 38c, 38d Fig. 1.

10 For narrowing the fabric the selvage stops Rs and Ls must be adjusted towards each other, or in other words, towards the center of the machine. For this purpose the brackets 36, which carry the said selvage stops, are engaged by a screw shaft 43 having the thread at one end reversed in direction in respect to the direction of the thread at the other end of the said shaft. This shaft is operated by band 43e from a lever (not shown) operated by a cam on the main cam shaft of the machine. The band operates a drum 25 43d carrying a pawl 43k engaging a ratchet on stub shaft 43c, which is geared to the screw shaft 43. The screw shaft in addition to being operable as just described by automatic mechanism for setting the stops Rs and Ls inwardly towards 30 the center of the machine, step by step for making the narrowings, is operable by hand by a crank 43j, whereby the stops may be returned outward away from each other to position for beginning a new fabric.

35 The narrowing points 44 are mounted on blocks, one of which is shown at 44a mounted on a screw shaft 44b by which said blocks are automatically adjusted towards the center of the machine in performing the narrowing operations. This screw shaft is operated automatically through 40 pawl and ratchet mechanism and gearing, which comprises pinion on the shaft 44b gear 44d on

stub shaft 44x, provided with a spring drum 44' operated by a steel band 44e. The drum carries a pawl 44f, which engages a ratchet 44g fixed on the stub shaft. The band 44e is operated from the main cam shaft through the same cam thereon, and the same lever which operates the band first mentioned.

5 The narrowing points are carried by a narrowing frame 47 having movement up and down in the operation of transferring stitches from needle 10 to needle.

The machine above described embodies features like those disclosed in application of the United States filed by Kenneth Howie and Charles Krieble Feb. 4, 1932, Ser. No. 590,942, Patent No. 15 1,982,991, in which some of the mechanism concerned herein is illustrated in greater detail.

The machine will produce fashioned fabrics in which only one yarn is used.

20 We claim:

A one feed full fashioned knitting machine comprising a straight row of needles, only one yarn guide, only one endless flexible band, said band being of substantially flat form in cross section and having a stretch for traversing said 25 yarn guide along the needle row with strokes equal in length to those of said band, reciprocating driving means for the band engaging the more remote stretch of the band which lies opposite to the stretch first mentioned, automatically 30 adjustable stop means engaging said remote stretch of the band for arresting said band variably as to its lengths of stroke, said driving means comprising a member carrying a pawl, means on the said driving member for setting the pawl in 35 position to drive the endless band, and stationary contact means at each end of the stroke of the driving member for operating said pawl setting means.

KENNETH HOWIE.
CHARLES C. KRIEBLE.
